UNITED STATES PATENT OFFICE

2,609,203

SIMULATED BOWLING GAME

Frank J. Bula, Speedway, Ind., assignor of one-third to Vincent T. Connor and one-third to Theodore Kruse, both of Chicago, Ill.

Application December 1, 1948, Serial No. 62,807

8 Claims. (Cl. 273—85)

1

This invention relates to certain new and useful improvements in coin-controlled amusement bowling game apparatuses. A principal object of the invention is to utilize a spot of light to simulate a ball moving toward a plurality of targets, together with an arrangement for moving the spot of light.

Another object of this invention is to provide a novel and entertaining arrangement for controlling and directing the ball-simulating spot of light in its travel toward a target area.

Another object of the invention is to provide an amusement game apparatus which requires of the player a high degree of skill.

In most amusement game apparatuses of the coin-controlled type, a ball is projected to the upper end of an inclined board for gravitation thereover into and against one and more targets thereon. In such games, after the ball has been projected for gravitation over the board by a projector, the ball is no longer under the control of the player. In many localities, such an apparatus is labeled a "game of chance" and its operation forbidden. In the amusement game apparatus embodying my invention, the spot of light which simulates the moving ball is at all times under the control of the player, thereby constituting the game apparatus a game requiring substantial skill in its operation. By reason of this fact, the amusement game apparatus constituting the subject matter of my invention is one of skill.

Another and equally important object of the invention is to provide a simple and inexpensive mechanism for projecting and guiding the spot of light, simulating a moving ball to the target area, upon a translucent playing field.

Finally it is an object of this invention to provide an amusement game apparatus which is not only a game of skill but also one which will afford the maximum amusement and entertainment to the player.

Other objects will appear hereinafter.

The invention consists in the novel combination and arrangement of parts to be hereinafter described and claimed.

The invention will be best understood by reference to the accompanying drawings showing the preferred form of construction, and in which:

Fig. 1 is a perspective view of the amusement game apparatus embodying my invention;

Fig. 2 is a part longitudinal vertical sectional detail view of the same;

Fig. 3 is a fragmentary sectional detail view taken substantially on line 3—3 of Fig. 2;

Fig. 4 is a fragmentary detail sectional view taken substantially on line 4—4 of Fig. 2;

Fig. 5 is a side elevational view taken substantially on line 5—5 of Fig. 3;

2

Fig. 6 is a fragmentary sectional detail view taken substantially on line 6—6 of Fig. 4;

Fig. 7 is a fragmentary sectional detail view taken substantially on line 7—7 of Fig. 6;

Fig. 8 is a side elevational view of a resetting arm and its mounting embodied in the invention;

Fig. 9 is a plan view of the same;

Fig. 10 is a fragmentary sectional detail view of certain parts shown in Fig. 5 showing such parts in different position with respect to each other;

Fig. 11 is a perspective view of a target striker embodied in the invention;

Fig. 12 is a diagrammatical view of a circuit arrangement embodied in the invention;

Fig. 13 is a fragmentary sectional detail view taken substantially on line 13—13 of Fig. 3; and

Fig. 14 is a sectional detail view of one of the bowling pins embodied in the invention.

The invention in its preferred form of construction, and by which construction the several objects of the invention are accomplished, includes (Fig. 1) a cabinet 20 comprising a supporting top wall 21 and a base 22. In the form of the invention illustrated in the drawings, the top wall 21 provides a bowling alley 23 comprising the side walls 24, end walls 25, a top transparent cover plate 26, and a translucent playing field 27.

At one end of the alley 23 is a mounting board 28. On this board 28, in standard formation, are arranged bowling pins 29. Each of these bowling pins 29 is formed of translucent material and has arranged therein an incandescent lamp 30.

The front wall 22 of the cabinet 20 has an opening 31 formed therein. Mounted on this front wall 22 and framing the opening 31 is an escutcheon plate 32. Within this escutcheon plate 32 and in the opening 31 is a body 33 (hereinafter referred to as a "hand plate") simulating the hand gripping side of a bowling ball. In this hand plate are provided finger gripping openings 34 and 34'. Arranged in one of the openings 34 is a push button switch 35 of a standard construction.

On the front wall 22 is mounted a coin slide 37 including a slide bar 38. This coin slide 37 is of a well known construction and is commonly used in connection with coin-controlled ball rolling games. This coin slide constitutes no part of the present invention.

To complete the cabinet, there is provided (Fig. 1) at the end thereof an upright cabinet 36 within which may be arranged a suitable score mechanism (not shown). This score mechanism constitutes no part of the present invention.

Extending from the front wall 22 of the cabinet 20 (Figs. 2 and 5) and secured thereto in any suitable manner is a laterally extending bracket

39. This bracket at its extremity provides a bearing 40.

Secured to a mounting board 41 (Figs. 2 and 5) arranged within the cabinet in spaced relation with respect to the translucent playing field 27 is a plate 42 providing a bearing 43.

Arranged between the bearings 40 and 43 and having its end portions journalled therein, is a vertically extending rotatable shaft 44 properly positioned with respect to the bearings 40 and 43 by collars 45 carried by and fixed to the shaft 44. The shaft 44 fixedly carries a block 46. A U-shaped bracket 47 has its parallel arm portions 48 spaced from the adjacent sides of the block 46.

Arranged between these arms 48 and the block 46 and insulated therefrom by insulating plates 49 are the end portions 50 of track bars 51. These track bars 51 are connected between the arms 48 of the brackets 47 and the block 56 by suitable screws 52 which screws (Figs. 2, 3 and 5) connect the bracket to the block 46 and are spaced from the track bars 51 by passage through enlarged openings 46' formed in the bars 51. The bracket 47 has a depending apron 53.

A nut-bearing bolt 54 rigidly connects the spindle 55 of the hand plate 33 to the apron 53 of the bracket 47. This spindle 55 is further connected to the shaft 44 by a stabilizer 56 comprising an L-shaped plate 57 connected by means of screws 58 to a block 59 in turn rigidly connected to the shaft 44 (Figs. 2, 3 and 5).

For reasons hereinafter more apparent, a bumper ring 60 is mounted on the shaft 44 above the block 46.

A supporting arm 61 (Figs. 2, 3 and 5) is secured as at 62 to the shaft 44 for rotation therewith. Supported as at 62' to the free end portion of this arm 61 is an electrically operated solenoid 63. The coil 64 of this solenoid 63 is connected by conductors 65 to a power source 66 and to the push button 35 in the manner shown in Fig. 5. Each time the switch of the push button 35 is closed by pressure of the thumb of the hand thereon, the coil 64 will be connected in circuit with the power source, for reasons hereinafter apparent.

The plunger 67 of the solenoid 63 by means of a link 68 is pivotally connected as at 68' to a throw arm 69. One end of this throw arm 69 is pivotally connected to the supporting arm 61 as at 69'.

The upper end portion of the throw arm 69 is turned about its longitudinal axis to provide a flat surface 70 which is adapted to engage the angled end portion 71 of a target striker 72 carried by a carriage 73. In the position of the throw arm as shown in Fig. 5 the end portion 70 thereof bears against the bumper 60.

The carriage 73 includes parallel confronting side plates 74 and 75 formed of non-conductive material. These plates 74 and 75 are spaced from each other by suitable spacer bars 76 likewise formed of non-conductive material and connected to the side plates 74 and 75 by suitable connecting screws 77.

The side plate 74 has connected thereto by means of suitable stud shafts 78, grooved wheels 79 which rollingly engage the adjacent track rail 51.

The side plate 75 intermediate its opposite end portions and on a line midway between the wheels 79, carries a roller 80 which rollingly bears against the adjacent track rail 51. This roller 80 is mounted on a stud shaft 81. This stud shaft 81

carries a conductor strip 82 bent substantially U-shaped with the end portion 83 thereof engaging the rounded end portion 84 of the shaft 81. To this conductor strip 82 is connected as at 85 a conductor wire 86.

Carried by one of the stud shafts 78 (Fig. 3) and angled to bear against the inner end thereof as at 79' is a substantially U-shaped conductor strip 78'. This strip 78' together with a conductor wire 87, connected as at 88 to the said one of the stud shafts 78, provides a connection between the one stud shaft 78 and a terminal block 89 of a socket mounting 90 of any approved construction. To this block 89 is also connected the conductor wire 86. The socket mounting 90 may be of any approved construction and is arranged within a housing 91 and supports an incandescent lamp 92. This incandescent lamp 92 is arranged beneath a lens assembly 93 of any approved construction which, when the incandescent lamp 92 is illuminated, projects a spot of light against the translucent plate 27. This spot of light is plainly visible through the plate and simulates a ball.

This housing 91 is mounted upon a plate 93' formed of non-conductive material, and this plate is connected to the spacer bars 76 as at 94.

The target striker 72 includes a disc-shaped member 95. This disc 95 has its flat surfaces disposed in a substantially horizontal plane so that the edge 96 of the striker disc will engage the switch posts 126 for reasons hereinafter more fully explained.

This striker disc is secured as at 97 to an arm 98 which is secured as at 99 to a substantially U-shaped bracket 100. This parallel arms 101 of this bracket are pivotally connected as at 102 to the side plates 74 and 75. The ends of these arms 101 are connected to over-throw springs 103 arranged between pins 103' carried by brackets 104 secured to the side plates 74 and 75 and the arms 101 (Figs. 5 and 11).

The end portion 71 of the target striker 72 is provided with a forwardly extending finger 71' which is adapted to engage a projection 105 carried by the throw arm 69.

The tracks are connected to the source of electric energy 66 as diagrammatically illustrated in Fig. 3 by conductors 106. The arrangement is such that when the "time switch" 157 is closed by operation of the coin slide 37, the incandescent light 92 will be energized to project the spot of light upon the playing field 27. This time switch is of a well known standard construction and constitutes no part of my invention. It includes an actuating arm 157' adapted to be engaged by the coin slide 37. Other arrangements may be provided for energizing the incandescent light 92 and I therefore do not wish to be limited to the circuit arrangement illustrated in Fig. 5 of the drawings herein which circuit is here shown for illustrative purposes only.

Between the side walls 20' of the cabinet 20 at the inner end of the cabinet 20 is mounted a transversely, horizontally extending supporting bar 107 which serves to support the track bars at an inclination with respect to the horizontal (Fig. 4). The track bars 51 at the inner end portion are spaced by a spacer block 108, insulated from the track bar by means of insulating inserts 109 (Fig. 4). To these end portions of the track bars 51 are secured as at 110, L-shaped bearing arms 111 from which extend stud shafts 112. On these stud shafts 112 are rotatably arranged wheels 113, which ride upon

the track bar 107 and serve to support the track bars inclined in a direction upwardly from the front wall 22 of the cabinet.

The inner end portions of the track bars 51 carry on corresponding sides thereof, rubber bumpers 114, which bumpers are designed to engage the sides 74 and 75 of the carriage to rebound the carriage back upon the inclined track bars 51.

The side plates 74 and 75 (Fig. 5) at their lower corresponding corners have secured thereto, stud shafts 115. Mounted on these stud shafts 115 are rollers 116 which serve to prevent displacement of the carriage from the track rails.

The side plate 75 intermediate the rollers 116 carries a stud shaft 117. Mounted on this shaft 117 is a roller 118 which engages the adjacent track rail 51. This stud shaft 117 is connected by a suitable connector 119 to the stud shaft 81 (Fig. 13). The roller 118 cooperates with the roller 80 to assure a positive contact with the adjacent track bars 51.

Slidably supported by spaced set screws 120, upon the spacer rods 76 similar to and serving the same purpose as the spacer bars 76, is a reset bar 121 of flat elongated formation. The end portion 121' of this reset rod 121 is bent radially with respect to the long axis thereof to provide a vertically extending striker edge which is adapted to engage the angled end portion 71 of the arm 98 of the striker 72.

In its normal starting position, the carriage 73 is releasably latched upon the track bars. This is accomplished through the medium of a latch finger 51' secured to the block as at 52' and having its latch head 53' engaging the adjacent spacer bar 76 which bar 76 has a groove 54' to receive the latch head. The latch finger is disengaged from the carriage by the action of the throw arm 69. By this provision of the latch finger, the carriage cannot be moved forwardly upon the track by tilting the cabinet 20.

Mounted upon the board 41 (Figs. 6-7) by means of supporting brackets 122 is a supporting platform 123 of non-conductive material. Supported by and above this platform 123 is a relatively flat conductor plate 124. This plate 124 is supported in spaced relation with respect to the platform 123 by spacer rods 125.

Carried by the platform 123 are a plurality of flexible switch posts 126. These posts extend upwardly from the platform 123 through openings 127 formed in the conductor plate 124 and are normally spaced from the conductor plate 124 as shown in Fig. 7.

Each post 126 comprises a base 128 connected to the platform by means of a screw 129. This base 128 has a tapered reduced projection 130 which extends into a socket 131 formed in an intermediate section 132 and normally in contact therewith. This intermediate section 132 has a socket 133 into which a reduced tapered portion 134 projects and which is normally in contact with the intermediate section. This projection 134 is formed as an integral part of a post section 135 having a cap 136. These sections are formed of conductive material and are flexibly connected together by means of a spring 137 projected through a bore formed in the sections and having one end portion connected as at 138 to the base 128 and an opposite end portion connected as at 139 to the cap 136.

The arrangement is such that when the edge 96 of the striker disc 95 strikes one or more of

the posts 126, the sections of each post, being yieldably connected together, will assume substantially the position shown in dotted lines in Fig. 7, to bring the intermediate section 132 into contact with the conductor plate 124. The post section 135, being yieldably connected to the intermediate section, will be free to tilt a sufficient distance to permit the full travel of the carriage upon the track bars 51 in the manner and for the reasons presently to be explained.

As shown in Fig. 12 each incandescent lamp 30 of the pins 29 (which pins are arranged in standard bowling formation) has one side connected by a conductor 140 to one side 141 of a relay switch 142. The switch arm 143 of this relay switch is controlled by an overthrow spring 144 of any approved construction, and which will hold the arm 143 on either side of a center line between relays 148 and 149.

20 This switch arm 143 is connected by a conductor 145 to one side of a power source 146 the other side of such source being connected by conductors 147 and 147 to the other side of the incandescent lamp 30.

25 This switch arm 143 is actuated by a conductor 145 to one side of a power source 146 the other side of such source being connected by conductors 147 and 147 to the other side of the incandescent lamp 30.

30 The switch arm 143 is actuated by the confronting electromagnetic relays 148 and 149.

The relay 148 has one side connected by means of a conductor 150 to one of the posts 126. The conductor plate 124 is connected by a conductor

35 151 to one side of the power source 146, the other side of the power source being connected by conductors 147 and 152 to the other side of the relay 148.

35 One side of the relay 149 is connected by a conductor 153 to one side of a coin slide actuated switch 154, the other side of such switch being connected by a conductor 155 to one side of the power source 146, the other side of the power source 146 being connected by conductors 147 and 156 to the other side of the relay 149.

40 Each of the incandescent lamps 30 in the pins 29 simulating the bowling ball pins, is arranged in a circuit similar to that shown in Fig. 12. The object is to maintain the incandescent lamp illuminated until the game has been played during a period of time permitted by a timing switch 157 incorporated in the electric circuit shown diagrammatically in Fig. 5.

45 The switch structure 154 is adapted to be closed by the coin slide bar 38 when this bar 38 reaches its full stroke position.

50 The operation of the game apparatus is as follows:

55 A coin is inserted in the coin slide 37. This coin slide 37 sets the time switch 157 in motion and closes the switch element 154 to energize the electromagnetic element 149 to move the switch arm 143 from contact with the switch element 141 to de-energize the incandescent lamps. The time switch will also complete the circuit to the lamp 92. The operation of the timing switch places the electromagnetic solenoid 64 in circuit with the power source 66 to be energized upon closing of the push button switch 35.

60 The player will grip the hand plate 33 in the manner of gripping a bowling ball. The player will horizontally adjust the track by rotating the shaft 44. In doing so, the player will position the carriage for travel along a path upon the track bars which in the player's judgment will result in what is known in the bowling ball game as a "strike." When he has thus positioned the carriage, he places his thumb upon the push button thereby to energize the solenoid 63. The solenoid will pivot the throw arm 69 to propel

the carriage along the track bars 51. In this movement of the carriage, the target striker 72, being in the position shown in Figs. 2 and 5, will be brought into contact with the heads 136 of the posts 126 and will cause all or certain of these posts to be tilted to bring the intermediate sections 132 of such tilted posts into contact with the plate 124.

As the incandescent lamp supported by the carriage 73 is illuminated, during the travel of the carriage along the track rails, the spot of light will move upon the translucent playing field 27, simulating a ball traveling toward the pins 29. Certain or all of these pins 29 will be illuminated depending upon which of the posts 126 are tilted by the striker disc 96 carried by and movable with the carriage 73. The illumination of these posts is effected by the movement of the switch arm 143 into contact with the switch element 141 upon energization of the relay 148, which energization of the relay 148 is effected by contact of the switch post 126 with the conductor plate 124. The lamp will remain illuminated until the switch 154 is closed by the operation of the timing switch at which time the electromagnetic element 149 will be energized to break the circuit to the lamp 30.

When the carriage reaches the end of its run in target direction upon the track rails 51, the reset rod 121 will engage a strike plate 122' and be moved longitudinally of the carriage in a direction opposite to the travel thereof. This engagement of the reset rod with the strike plate 122' will bear the reset rod 121 against the angled end portion 71 of the target striker 72 and cause the same to pivot in an anti-clockwise direction as viewed in Fig. 5 to pivot the striker disc 96 in the position illustrated in Fig. 10, in a plane above the posts 126 so that when the carriage is returned by the gravity to its starting position, the target striker will clear the posts 126.

After the throw arm 69 has been pivoted in a clockwise direction as viewed in Fig. 5, it will remain in that position until returned to its normal position of rest in the following manner:

The track bars 51 as shown in Fig. 2 are inclined with respect to the horizontal so that the carriage will be caused by gravity to return to its starting position. Just prior to reaching its starting position, the carriage will engage the finger 71' above the head 105 of the throw arm 69. The momentum of the carriage during its travel to its starting position will pivot the throw arm 69 in an anti-clockwise direction as viewed in Fig. 10. As this throw arm 69 is thus pivoted to its normal initial position, the head 105 will bear upon the finger 71', pivot the arm 98 to the position shown in Fig. 5, and at the same time re-project the reset rod 121 to the position shown in Fig. 5.

The essential and important feature of my invention is the provision of means for movably supporting an incandescent lamp to project a moving light spot upon a translucent plate to simulate the movement of a ball rolling upon the plate in a direction toward the targets. In the present instance, I have accomplished this by the provision of a carriage adapted to be projected along a track-way by an electromagnetic element. This track-way is adjusted by the player to direct the travel of the carriage and consequently the spot of light upon the translucent playing field. I have found that by adjusting the track-way laterally that the spot of light can be caused to curve in its travel toward the targets.

While I have illustrated diagrammatically cer-

tain diagrams for controlling the various electric elements, it is to be understood that these circuits are merely suggestive circuits and that these circuits may be varied in order to accomplish the desired and best result in the most efficient and inexpensive manner.

It is apparent that the amusement game apparatus embodying the principles and constructed in accordance with the foregoing description is one which calls upon the player to exercise a high degree of skill.

While I have illustrated and described the preferred form of construction for carrying my invention into effect, this is capable of variation and modification without departing from the spirit of the invention. I therefore, do not wish to be limited to the precise details of construction set forth, but desire to avail myself of such variations and modifications as come within the scope of the appended claims.

Having thus described my invention, what I claim as new and desire to protect by Letters is:

1. An amusement game apparatus comprising a cabinet having a translucent playing field, a plurality of translucent pins simulating bowling ball pins arranged at one end of said playing field, an incandescent lamp arranged in each of said pins, an electric circuit including a power source for said lamps, switch means in said circuit including flexible switch posts arranged in said cabinet beneath said translucent playing field, a movable member arranged in said cabinet beneath said playing field and having means adapted to strike one or more of said switch posts to close said circuit and means for projecting said member in a direction toward said switch posts, said movable member including means for projecting a spot of light against the translucent playing field.

2. An amusement game apparatus comprising a cabinet having a translucent playing field, means for projecting a spot of light upon said field, an inclined track arranged in said cabinet, means for supporting said track for movement in a horizontal plane about a vertical axis, hand gripping means for moving said track about said axis, a carriage movably carried by said track and supporting said light projecting means and means for projecting said carriage in one direction along said track, said carriage being movable in an opposite direction upon said track by gravity, said carriage projecting means including a pivotally movable throw arm, and an electromagnetic element for moving said throw arm into projecting engagement with said carriage.

3. An amusement game apparatus comprising a cabinet having a translucent playing field, a plurality of translucent pins at one end of said playing field and simulating bowling ball pins, an incandescent lamp arranged in each of said pins, a power circuit for said incandescent lamps, switch posts incorporated in said circuit for controlling illumination of said lamps, means movably supported within said cabinet and having an element adapted to strike one or more of said switch posts to effect illumination of said lamps by said power circuit, and means carried by and movable with said last-named means for projecting a spot of light upon said translucent playing field to simulate a rolling ball striking the lamps as illuminated by action of said switch posts.

4. An amusement game apparatus comprising a cabinet having a translucent playing field, a plurality of translucent pins at one end of said

playing field and simulating bowling ball pins, an incandescent lamp arranged in each of said pins, a power circuit for said incandescent lamps, switch posts incorporated in said circuit for controlling illumination of said lamps, means movably supported within said cabinet and having an element adapted to strike one or more of said switch posts to effect illumination of said lamps by said power circuit, and means carried by and movable with said last-named means for projecting a spot of light upon said translucent playing field to simulate a rolling ball striking the lamps as illuminated by action of said switch posts, and means including a hand gripping element for directing the path of movement of said movable means.

5. An amusement game apparatus comprising a translucent playing field, a plurality of translucent elements at one end of said field, an incandescent lamp within each of said elements, an electric circuit for said lamps including a plurality of switch members, means for projecting a spot of light upon said field, means for supporting said light projecting means for movement relative to said field, said last-named means having an element adapted to engage one or more of said switch members to close the circuit to said incandescent lamps.

6. An amusement game apparatus comprising a translucent playing field, a plurality of translucent elements at one end of said field, an incandescent lamp within each of said elements, an electric circuit for said lamps including a plurality of switch members, means for projecting a spot of light upon said field, means for supporting said light projecting means for movement relative to said field, said last-named means having an element adapted to engage one or more of said switch members to close the circuit to said incandescent lamps, and means for directing the movement of said light supporting means.

7. An amusement game apparatus comprising a translucent playing field, a plurality of translucent elements at one end of said field, an incandescent lamp within each of said elements, an electric circuit for said lamps including a

plurality of switch members, means for projecting a spot of light upon said field, means for supporting said light projecting means for movement relative to said field, said last-named means having an element adapted to engage one or more of said switch members to close the circuit to said incandescent lamps, and means for directing the movement of said light supporting means, said last-named means including a hand gripping member.

8. An amusement game apparatus comprising a cabinet having a translucent playing field, a plurality of translucent targets on said playing field, an incandescent lamp arranged to illuminate each of said targets, a power circuit for said incandescent lamps, switch posts incorporated in said circuit for controlling illumination of said lamps, means movably supported within said cabinet and having an element adapted to strike one or more of said switch posts to effect illumination of said lamps by said power circuit, and means carried by and movable with said last-named means for projecting a spot of light upon said translucent playing field to simulate a rolling ball striking the lamps as illuminated by action of said switch posts.
